UNITED STATES PATENT OFFICE.

CHARLES C. WANBAUGH, OF NEW DORP, NEW YORK.

SHADE HOLDER.

Application filed May 14, 1926. Serial No. 102,996.

The present invention relates to shade holders and is more particularly directed toward a screwless shade holder suitable for supporting glass shades commonly used in enclosed lighting units.

The present invention contemplates an improved shade holder made up of a small number of sheet metal stampings which may be assembled into a shade holder and in which no screws or other detachable members are used.

An object of the present invention is to provide a shade holder from which a shade, globe or lighting unit may be supported and having a two part shelf or flange composed of semi-circular halves, one of which may be moved adjacent the other to facilitate the removal of the shade.

The accompanying drawings show, for purposes of illustrating the invention, one of the many possible embodiments in which it may take form, it being understood that it is illustrative of the invention rather than limiting the same.

In these drawings:

Fig. 1 is a side elevational view of a shade holder;

Fig. 2 is a vertical sectional view of the same;

Fig. 3 is a perspective view of the revolvable cap or cover;

Fig. 4 is a perspective view of a revolvable portion of the shade holder having one-half of the shade supporting shelf;

Fig. 5 is a perspective view of the stationary part of the shade holder having the other half of the shelf; and

Fig. 6 is a perspective view illustrating the position of the parts when a shade is being inserted into or removed from the shade holder.

A bell shaped sheet metal stamping 10, shown more in detail in Fig. 5, is adapted to carry the lamp socket 11, indicated in dotted lines. This bell-shaped stamping is provided with an outwardly directed semi-circular flange 12 and with a number of threads 13 spaced some distance above the bottom of the bell-shaped stamping.

A revolvable member 14 is carried by the lower end 15 of the bell-shaped stamping. This revolvable member has a cylindrical band 16 which fits the outside of the stamping and the lower edge of which rests on the upper edge of the flange 12. The revolvable member 14 is provided with an out-

wardly directed semi-circular flange 17 similar to the flange 12 carried on the bell-shaped stamping. The flange 12 is downwardly offset as indicated at 18 and the ends 60 of this flange are stepped as indicated at 19 and 20. Stops 21 and 22 are also struck out of the material of the flange 12. The flange 17 on the revolvable member is downwardly offset as indicated at 23 similar to 65 the offset 18 in the flange 12.

A sheet metal cap 24 is adapted to pass downwardly around the outside of the bell-shaped stamping 10. This cap has inwardly directed prongs 25 which preferably do not 70 engage with the upper part of the stamping 10, but which are able to cooperate with the threads 13. The skirt 26 of the cap is adapted to cover the lip 27 of a globe, shade, or the like.

When one desires to insert a shade into the holder, it is merely necessary to unthread the cap to bring the lugs 25 free of the threads 13. The cap may then be lifted upwardly as indicated in Fig. 6. One may 80 then grasp the band 16 and turn it so that the flange 17 overlies the flange 12, as also indicated in Fig. 6, a bead 28 provided near the top of the band 16 preventing the fingers from slipping off the band. The shade may 85 be brought to a position such as indicated in Fig. 6 so that it may be passed onto the semi-circular shelf provided by the overlying flanges. After the neck of the shade has been passed above these flanges, one may 90 turn the revolvable member half way around bringing the ends of the flange 17 against the stops 21 and 22 carried by the stationary flange and allow the ends of the movable flange to rest in the depressed portions 19 95 and 20 of the stationary flange. The shade may then be allowed to rest on the circumferential flange provided by the two semi-circular flanges. The offsets 18 and 23 will facilitate centering the shade on the shade 100 holder. The cap 24 may then be lowered to bring the threads and lugs into registry and turned slightly to bring the lower edge of the cap against the top of the reflector. The cap finishes off the shade holder and 105 gives it a better appearance as well as assisting in holding the shade more firmly. When a shade is not in position, the cap will be held in place on the shade holder in an obvious manner.

It is obvious that the invention may be embodied in many forms and constructions

within the scope of the claims, and I wish it to be understood that the particular form shown is but one of the many forms. Various modifications and changes being possible, 5 I do not otherwise limit myself in any way with respect thereto.

What is claimed is:

1. A shade holder comprising a bell-shaped sheet metal stamping adapted to carry a 10 lamp socket and having an outwardly extending semi-circular flange at the lower end thereof, a revolvable member carried by the lower part of the stamping and having an outwardly extending semi-circular flange, 15 the revolvable member being movable so that the flanges may overlie one another to permit insertion or removal of a shade, or may be brought into a position to form a circumferential flange for supporting a 20 shade, and a cap carried outside the bell-shaped stamping and adapted to cover the lip or bead of the shade.

2. A shade holder comprising a bell-shaped sheet metal stamping adapted to 25 carry a lamp socket and having an outwardly extending semi-circular flange at the lower end thereof, and a revolvable member carried by the lower part of the stamping and having an outwardly extending semi- 30 circular flange, the revolvable member being

movable so that the flanges may overlie one another to permit insertion or removal of a shade, or may be brought into a position to form a circumferential flange for supporting a shade, the side walls of the bell-shaped stamping having threads, and a cap engageable with the threads and adapted to 35 cover the lip or bead of the shade.

3. A shade holder comprising a bell-shaped sheet metal stamping adapted to 40 carry a lamp socket and having an outwardly extending semi-circular flange at the lower end thereof, and a revolvable member carried by the lower part of the stamping and having an outwardly extending semi-circular flange, the revolvable member being 45 movable so that the flanges may overlie one another to permit insertion or removal of a shade, or may be brought into a position to form a circumferential flange for supporting a shade, the side walls of the bell-shaped stamping being threaded above the 50 revolvable member, and a cap threaded to the bell-shaped member and covering the revolvable member and shade lip.

Signed at New York, in the county of New York, and State of New York, this 12th day of May, 1926.

CHARLES C. WANBAUGH.
